UNITED STATES PATENT OFFICE.

WALTER H. WAKEFIELD, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETT.

DETECTOR FOR REGULARLY-MOVING TRANSFERRERS.

Application filed February 1, 1926. Serial No. 85,141.

This invention relates to improvements in the type of detectors mounted on a regularly reciprocating transerrer arm, and it is the principal object of the invention to provide means for holding the actuating plunger usually forming part of such a device in locked position.

It has been proposed heretofore to employ a spring pressed plunger slidably mounted in the transerrer arm and held in position by a pivoted latch which is unseated by the detector at substantial exhaustion of weft, but such devices are subject to objectionable motion either because of the quick descent of the transerrer arm or because of non-indicating engagement between the detector and the latch, and it is a further object of my invention to provide a latch slidably mounted in the transerrer arm movable in a direction transverse to the axis of the plunger, the latch being moved positively by the detector at substantial weft exhaustion to release the plunger. In making the latch movable substantially at right angles to the plunger and also at right angles to the motion of the detector as the latter slides along the bobbin said latch is not affected by accidental engagement with the detector.

With these and other objects in view which will appear as the description proceeds, my invention resides in the combination and arrangement of parts hereinafter described and set forth in the claims.

In the accompanying drawings wherein I have shown a convenient embodiment of my invention,

Fig. 1 is a vertical longitudinal section through the bobbin engaging portion of a transerrer arm having my invention applied thereto, showing the transerrer arm on the downward stroke with the detector in position about to be advanced to the surface to be detected,

Fig. 2 is a fragmentary view of portions of Fig. 1 showing the detector in engagement with a full bobbin,

Fig. 3 is a view similar to Fig. 1 but showing the detector as it starts to move under the latch at substantial exhaustion of weft,

Fig. 4 is a view similar to Fig. 1 but showing the detector moved entirely under the latch with the transerrer arm in its low-

est position to hold the latch raised as the arm descends and release the plunger; and 55

Fig. 5 is a vertical transverse cross section through the transerrer arm taken on line 5—5 of Fig. 3.

Referring to the drawings, I have shown a transerrer arm 10 having a forwardly extending supporting portion 11 and having a shoe 12 to engage the butt of the bobbin. By means of mechanism not shown the transerrer arm 10 is reciprocated, being brought down to the surface to be detected when the shuttle is on the transerrer side of the loom and being raised immediately thereafter to give an indication to the weft replenishing mechanism should a fresh supply of filling be needed. An actuating plunger 13 is slidably mounted in the arm and has a shoulder 14 defined by a reduced end 15. The latter extends through an upwardly extending web 16 of the arm and a compression spring 17 lies between the shoulder 14 and the web 16, tending normally to push the plunger to the right from the position shown in Fig. 1 to that shown in Fig. 4.

A detector supporting lever 18 is pivoted as at 19 to the transerrer arm and has on one end thereof a laterally projecting lug 20 positioned to engage a yielding pad 21 movably mounted on fixed structure. The other end of said lever 18 has pivotally mounted thereon as at 22 a weft detector 23 having a bobbin engaging tip 24. A pin 25 carried by the plunger engages the web 16 when the plunger moves to the position shown in Fig. 4 to limit movement thereof.

The left end of the plunger has a notch 26 which defines a head 27 for a purpose to be set forth. The matter thus far described is of known construction and forms no part of my present invention.

In carrying out my improvements I provide a latch 30 having a relatively long leg 31 and a relatively short plunger engaging leg 32. Said latch may conveniently be bent from bar stock and the lower end of leg 32 is beveled as at 33 so that the chamfered head 27 of the plunger can lift said latch against the action of leaf spring 34 secured to the transerrer arm. Said spring 34 is held to the transerrer arm by means of screws 35 one of which retains a clip 36 to which is attached one end of tension spring

37. Said spring 37 passes through an opening in lever 18 and is held to the latter by a pin 38. The purpose of the spring 37 is to hold the lever 18 in the position shown in Fig. 1. The upper face of the yarn engaging tip 24 is inclined as at 39 to insure proper co-action with the long leg 31 of the latch.

In operation when sufficient yarn for continued weaving is present the arm 10 will be lowered on each detecting beat and the tip 24 will be moved into engagement with the bobbin as shown in Fig. 2. As the weft of the bobbin B is exhausted, however, the tip 24 will slide along the bobbin when the transerrer arm is moved down, assuming first the position shown in Fig. 3 when the transerrer arm is slightly above its lowermost position and then moving under the leg 31 of the latch as shown in Fig. 4, so that further descent of the arm 10 will carry the head 27 of the plunger below the plunger engaging beveled end 32 and spring 17 will act to move the plunger 13 to the actuating position shown in Fig. 4.

It occasionally happens that the detector tip 24 will move laterally into engagement with the lower portion of the latch as indicated in dotted lines in Fig. 2 but such motion will not lessen the effectiveness of the latch to hold the plunger. The purpose of the inclined face 39 is to permit the detector 23 to be restored to the position shown in Fig. 1 without being caught under leg 31 of the latch.

From the foregoing it will be seen that I have provided a weft detector of the type mounted on a transerrer arm having a plunger retained in inoperative position by means of a member which slides transversely of the axis of the plunger and is positively raised relatively to the plunger as the transerrer arm descends on an indicating beat toward an exhausted bobbin, the latch being unaffected by lateral contact with the detector when the latter has non-indicating accidental movements when in contact with a substantially full bobbin.

Having thus described my invention it will be apparent that changes and modifications may be made therein by those skilled in the art without departing from the spirit and scope of the invention, and I do not wish to be limited to the details herein disclosed, but what I claim is:

1. In a weft detector for looms having a transerrer arm movable toward the weft

supply, a pair of sliding members mounted on the transerrer arm, means normally tending to move one of said members toward operative position and in holding engagement with the other member, and a weft detector movable at substantial weft exhaustion into engagement with one of said members to cause relative movement thereof with respect to the other member to release said other member whereupon said means will move said released member into operative position.

2. In a weft detecting mechanism for a loom having a transerrer arm movable toward the weft supply to be detected, a spring pressed member movable with respect to the arm, a latch slidably mounted on the transerrer arm and having engagement with the member and moving in a path transverse to the path of the member, and a detector movable at substantial exhaustion of weft into engagement with the latch to cause relative sliding movement thereof with respect to the arm as the arm moves toward the weft supply to release the member.

3. In a weft detector for looms having a transerrer arm movable toward the weft supply to be detected, a plunger slidably mounted on the transerrer arm and tending to move to operative position, a latch slidably mounted on the transerrer arm and having engagement with the plunger to hold said plunger in inoperative position, said latch being mounted for movement in a direction transverse to the axis of the plunger, and a weft detector movable at substantial weft exhaustion into engagement with the latch to cause relative movement of the latter with respect to the plunger.

4. A weft detector for looms having a transerrer arm movable toward the supply to be detected, a pair of sliding members each normally spring pressed toward operative position, said members having holding engagement with each other so that one of them when in operative position holds the other in inoperative position, and means operative at substantial weft exhaustion to engage the sliding member normally in operative position and move the same relatively to the other member to release said other member so that the same may move to operative position.

In testimony whereof I have hereunto affixed my signature.

WALTER H. WAKEFIELD,
